BY H. J. Fisher ATTY

UNITED STATES PATENT OFFICE.

GEORGE H. DIPPO, OF CHAGRIN FALLS, OHIO.

DESIGN FOR A HANDLE-TUBE.

SPECIFICATION forming part of Design No. 24,704, dated September 24, 1895.

Application filed August 24, 1895. Serial No. 500,438. Term of patent 14 years.

To all whom it may concern:

Be it known that I, GEORGE H. DIPPO, a citizen of the United States, residing at Chagrin Falls, in the county of Cuyahoga and 5 State of Ohio, have invented and produced a new and original Design in Handle-Tubes for a Combined Shovel and Peen, of which the following is a specification, reference being had to the accompanying drawings, showing

o a part thereof.

Figure 1 is a perspective view of a handle-tube, showing my design. Fig. 2 is an end elevation thereof.

The novelty of my design is found in the 5 peculiar shape or configuration of the handle-tube, the said tube having three distinguish-

ing and original features not hitherto known and combined in an article of this kind, and consisting of the transversely-rounded lower portion 2, the inwardly - converging and slightly-rounded sides 3, and the straight flat top surface 4, upon which the said sides terminate and which is considerably narrower than the rounded surface 2 at the bottom of the tube. 25

What I claim is—

The design for a handle tube for a combined shovel and peen, as shown and described.

GEORGE H. DIPPO.
